US00D889977S

(12) **United States Design Patent** (10) **Patent No.:** **US D889,977 S**
(45) **Date of Patent:** **** Jul. 14, 2020**

(54) **PACKAGING**

(71) **Applicant:** **THE GLAD PRODUCTS COMPANY**, Oakland, CA (US)

(72) **Inventor:** **Michelle Michiko Shibata-Schwartz**, Oakland, CA (US)

(73) **Assignee:** **The Glad Products Company**, Oakland, CA (US)

(**) **Term:** **15 Years**

(21) **Appl. No.:** **29/679,611**

(22) **Filed:** **Feb. 7, 2019**

(51) **LOC (12) Cl.** **09-03**

(52) **U.S. Cl.**

USPC **D9/600; D9/418; D9/432**

(58) **Field of Classification Search**

Primary Examiner — Vy N Koenig

(74) *Attorney, Agent, or Firm* — Thomas C. Feix

(57) **CLAIM**

The ornamental design for packaging, as shown and described.

DESCRIPTION

FIG. 1 is a top, front perspective view of packaging showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The short dashed broken lines in the figures show portions of the packaging that form no part of the claimed design. The longer dashed broken lines show perforations and form part of the claimed design.

1 Claim, 4 Drawing Sheets
